UNITED STATES PATENT OFFICE

115,231

DESIGN FOR A CONTROL PANEL BOARD AND HOUSING FOR DENTAL X-RAY MA- CHINES

Edward B. Graves, South Euclid, and Robert J. Stava, East Cleveland, Ohio, assignors to Picker X-Ray Corporation, Waite Manufacturing Division, Inc., Cleveland, Ohio, a corporation of Ohio

Application February 20, 1939, Serial No. 83,110

Term of patent 7 years

To all whom it may concern:

Be it known that we, Edward B. Graves and Robert J. Stava, citizens of the United States and residents, respectively, of South Euclid and East Cleveland, Cuyahoga County, Ohio, have invented a new, original, and ornamental Design for Control Panel Board and Housing for Dental X-Ray Machines, of which the following is a specification, reference being had to the accompanying drawing, forming a part thereof.

In the drawing, Fig. 1 is a perspective view and Fig. 2 is a front elevation, of a control panel board and housing for dental X-ray machines, showing our new design.

We claim:

The ornamental design for a control panel board and housing for dental X-ray machines, as shown.

EDWARD B. GRAVES.
ROBERT J. STAVA.
